UNITED STATES PATENT OFFICE.

JOHN EDGAR HUDSON, OF HAVANA, NORTH DAKOTA.

METHOD OF EMBOSsing PRINTED MATTER.

No. 833,391.

Specification of Letters Patent.

Patented Oct. 16, 1906.

Application filed January 10, 1906. Serial No. 295,469.

To all whom it may concern:

Be it known that I, JOHN EDGAR HUDSON, a citizen of the United States, residing at Havana, in the county of Sargent and State 5 of North Dakota, have invented a new and useful Method of Embossing Printed Matter, of which the following is a specification.

This invention relates to a method of embossing printed matter.

10 The object of the invention is in a ready simple, thoroughly-feasible, and practical manner and without the use of metal plates for the purpose to emboss printed work of any character.

15 With the above and other objects in view, as will appear as the nature of the invention is better understood, the same consists in the method of embossing printed work, as will be hereinafter fully described and claimed.

20 In the accompanying drawings, forming a part of this specification, and in which like characters of reference indicate corresponding parts, Figure 1 is a perspective view of an embossing-form. Fig. 2 is a similar view 25 showing the procedure of making the embossing-die. Fig. 3 is a perspective detail view of the die.

The embossing-types are, by preference, 30 made of metal, with the letters and characters in intaglio. All of the letters of the alphabet, the figures, punctuation-marks, characters, borders, spaces, quads, and the like are made type-high, so that when locked in a chase they will present a perfectly smooth and even 35 surface.

The mode of embossing under the present 40 method is as follows: After a job has been printed with the ordinary type the chase containing them is removed, and the chase containing the embossing-type is substituted therefor and is secured in exactly the same position upon the bed as that occupied by the first-named chase. To a sheet of heavy 45 paper 2, cardboard, or the like that has been previously firmly secured to the platen by any suitable adhesive is applied an embossing compound 3, such as is commonly employed by printers in making stereotypes and other dies, and the press is then closed, there- 50 by forcing the compound into the depressions

of the embossing-type, producing thereby a die 4. The press is then opened, and the die is allowed to dry. Owing to the fact that both the chase containing the embossing-type and the die are rigidly fixed relatively to the 55 bed of the press and to the platen thereof, it will be seen that the type and die will be caused positively to register, so that the production of perfect embossed work is secured. After the die has become hardened the sheets 60 of the printed job are successively laid over the die with the printing characters in register with the cameo characters thereon, and when the press is closed the paper will be forced into the depressions of the embossing- 65 type and thereby effect the desired ornamentation.

It will be seen from the foregoing description that, while the procedure herein defined is simple, cheap, and ready of execution, 70 it will be thoroughly efficient for the purpose designed and may be carried into effect without the necessity of the employment of skilled or special workmen for the purpose. Furthermore, a font of embossing-type may 75 be used indefinitely for ornamenting work of any character.

I claim—

1. The herein-described method of embossing, which consists in setting up a facsimile of 80 a printed job with type having characters in intaglio and disposed in the same order as the type used for printing the job, securing the set-up type to the bed of a press, securing a sheet of suitable material to the platen of the 85 press, depositing a body of embossing composition on the sheet, closing the press to force the compound into the intaglio type to form a die having relief type, allowing the die to harden, placing a sheet, previously printed, 90 on the die with the printed characters thereon registering with the relief type, and then embossing it.

2. The herein-described method of embossing, which consists in setting up a facsimile of 95 a printed job with type having characters in intaglio and disposed in the same order as the type used for printing the job, securing the set-up type to the bed of a press, arranging a body of embossing composition on the platen 100

of the press, closing the press to force the compound into the intaglio type to form a die having relief type, allowing the composition to harden, placing a sheet, previously printed, on the die with the printed characters thereon registering with the relief type, and then embossing the sheet.

In testimony that I claim the foregoing as my own I have hereto affixed my signature in the presence of two witnesses.

JOHN EDGAR HUDSON.
